US00D860166S

(12) **United States Design Patent** (10) **Patent No.:** **US D860,166 S**
(45) **Date of Patent:** **** Sep. 17, 2019**

(54) **HEAD-MOUNTED WIRELESS
COMMUNICATION DEVICE**

(71) Applicant: **DisplayLink (UK) Limited**, Cambridge (GB)

(72) Inventor: **Jason Warren Alfred Young**, Cambridge (GB)

(73) Assignee: **DisplayLink (UK) Limited**, Cambridge (GB)

(**) Term: **15 Years**

(21) Appl. No.: **29/634,809**

(22) Filed: **Jan. 25, 2018**

(30) **Foreign Application Priority Data**

Oct. 30, 2017 (EM) 004426732
(51) **LOC (12) Cl.** **14-01**
(52) **U.S. Cl.** ..... **USPC** **D14/206; D14/192; D14/217**

Primary Examiner — Paula Allen Greene

CLAIM

The ornamental design for head mounted wireless communication device, as shown and described.

DESCRIPTION

FIG. 1 is a perspective view of a head-mounted wireless communication device, showing my new design;
FIG. 2 is a first side view thereof;
FIG. 3 is a second side view thereof;
FIG. 4 is a front view thereof;
FIG. 5 is a rear view thereof;
FIG. 6 is a top view thereof;
FIG. 7 is a bottom view thereof; and,
FIG. 8 is a further perspective view thereof.
The broken lines depict environment that forms no part of the claimed design.

1 Claim, 8 Drawing Sheets
